UNITED STATES PATENT OFFICE.

FRANK B. KENNEDY, OF NEW HAVEN, CONNECTICUT, ASSIGNOR TO THE RECORDING REGISTER & FARE BOX COMPANY, OF NEW HAVEN, CONNECTICUT, A CORPORATION OF CONNECTICUT.

FARE-BOX.

1,217,186.

Specification of Letters Patent.

Patented Feb. 27, 1917.

Application filed April 21, 1913. Serial No. 762,506.

To all whom it may concern:

Be it known that I, FRANK B. KENNEDY, a citizen of the United States, residing at New Haven, in the county of New Haven 5 and State of Connecticut, have invented certain new and useful Improvements in Fare-Boxes, of which the following is a specification, reference being had therein to the accompanying drawing.

- 10 This invention relates to fare boxes of that class having means to compute and register the total value of coins of different denominations deposited therein, and is in the nature of an improvement upon the fare box 15 shown and described in an application for patent filed February 7th, 1912, by Samuel P. Huntington, Ser. No. 675,967 and assigned to The Recording Register and Fare Box Company.
- 20 The object of the invention is to provide a fare box of this class which will be simple in construction and positive in operation, which will handle the coins rapidly when operated at a relatively low speed and which will register with absolute accuracy the total value 25 of the coins handled when actuated at a very high speed. To this end it is a further object of the invention to provide a movable member having coin-lifting devices, each of 30 which will lift a coin of any of the several denominations which the machine is designed to handle, and to positively prevent each lifting device from presenting more than one coin at a time in registering position; and further, to so construct and arrange the several parts of the machine that the coins will not become jammed or bind in such a manner as to interfere with the proper 35 operation of the mechanism. It is also an object of the invention to provide a device which will be differentially operated by the coins, as they are moved by the coin moving devices, to cause the counting mechanism to be actuated in accordance with the value of 40 each coin.

In the accompanying drawings, Figure 1 is a front elevation of a fare box embodying my invention, with the casing and a portion of the hopper removed; Fig. 2 is a rear elevation of a portion of such a box; Fig. 3 is a top, plan view of the same; Fig. 4 is a sectional view, taken on the line $\alpha-\alpha$ of Fig. 1 and looking in the direction of the arrows; Fig. 5 is a top, plan view with the counting

mechanism removed; and Figs. 6, 7 and 8 55 are detail views showing the successive positions of the wiper arm.

In these drawings I have illustrated one embodiment of my invention and have shown the same as comprising a base 1 on 60 which are mounted suitable frame members 2 which carry the superstructure or operative parts of the device and which also form guideways for the money box or drawer 3 in which the coins are deposited after they have 65 been registered. It will be understood that the whole mechanism illustrated in these drawings is to be inclosed in a suitable cabinet or casing and that this casing will comprise an inspection chamber or tortuous 70 passage with transparent walls through which the coin must pass on its way to the hopper and within which it may be retarded to permit of inspection. Such devices are well known in this art and form no part of the 75 present invention. Mounted upon the frame members 2 is a hopper 4 having an outwardly flared forward portion 5 and provided with a movable member having devices for moving the coins from the hopper. 80 The hopper, of course, may be of any suitable character and this movable member may be of any kind which will operate satisfactorily to move the coins from the hopper to registering position. In the present instance 85 this movable member comprises a rotary inclined disk 6 rotatable about the axis of a stud 7 which is mounted in a transverse frame member 8. The disk is not mounted directly upon the stud 7 but is rigidly secured to the bevel gear 9 which is journaled on the stud and meshes with a bevel pinion 10 on a vertical shaft 11, which shaft also has secured thereto a bevel gear 12 meshing with a bevel pinion 13 on a shaft 14 which 90 extends beyond the rear of the machine and beyond the cabinet and, in the present instance, is provided with an operating handle or crank 15. It will be understood that the disk or other movable member may be 95 actuated in any suitable manner, either by hand or by means of any suitable operating devices. Preferably the connection between the operating device or handle 15 and the gearing is a yielding one which will permit 100 the handle to yield in case any unusual resistance should be offered to the movement of any of the parts and will thus prevent the

breakage of these parts. As here shown the handle has a hub 16 in which is mounted a spring-pressed pin 17, the inner end of which rests normally in a recess 18 in a disk 19 5 rigidly secured to the shaft 14 on which the hub is loosely mounted. The tension of the spring is such that it will hold the pin normally in the recess and cause the disk and its several operating parts to rotate with the handle, but should extraordinary resistance 10 be offered to the rotation of the shaft, the pin will slip out of the recess and ride over the surface of the disk, thus permitting the handle to continue its rotation without injury to the mechanism.

I also prefer to provide the hopper near the lower portion thereof with a part which will yield to prevent the coins from becoming wedged between the disk and the outer 20 wall of the hopper when they pile one upon the other. In the present form of the device this yielding part is shown as a plate of resilient metal 5^a secured to the inner surface of the outwardly flared wall 5 of the hopper, 25 having its outer edge spaced away from the adjacent wall of said hopper and arranged close to the lower portion of the disk. Any piling up or wedging of the coins between the disk and this yielding member will cause 30 the latter to yield sufficiently to permit the coins to pass, thus destroying the wedging action and preventing any interference with the rotation of the disk.

The movable member, which, in the present instance, is the inclined disk, has suitable devices for engaging and lifting the coins from the hopper. Preferably, these devices are in the form of pockets or recesses and, in the present construction, each 35 pocket is formed by two lugs 20 and 21 projecting from the face of the disk and arranged in such relation to each other and to the side wall or flange 22 of the hopper as to form a pocket or seat which will receive and retain a single coin of any one 40 of the denominations which the device is adapted to handle. There are, in the present arrangement, six of these devices or pockets upon the disk and as they pass 45 through the lower portion of the hopper they will engage the coins which, owing to the shape of the hopper and the position of the disk, will lie flat against the disk, and move the coins upward out of the hopper. 50 The inside lug 21 is of a height no greater than the thickness of the thinnest coin to be handled. Consequently, as the pocket passes the plane of the axis of the disk any surplus coin or coins which may have been 55 carried upward with the coin which is properly seated in the pocket will fall by gravity, as will also any coin or coins, which, lying flat against the disk, may be moved up ahead of the coin which is in the pocket. I prefer, however, to provide means for posi- 60

tively removing these surplus coins should they become stuck either to the coin which is in the pocket or to the disk itself. I have, therefore, mounted near the side of the disk and above the horizontal plane of the axis 70 thereof a suitable wiper 23 which is in the form of a bent arm pivoted on a stud 24 and having its inner end arranged to extend across the path of the pockets or lifting devices on the disk. This arm has a 75 tapered nose 23^a and the movement of the arm is so timed that this tapered nose will cross the path of the coin lifting devices immediately in the rear of each device as it passes the point at which the arm is located. 80 The inner face of the arm is so arranged that when it extends across the path of the coin lifting devices it will lie close to the face of the disk, and further, the edge of the arm is so shaped that it will extend at 85 an angle to the path of the coin lifting devices. Thus, any coin or coins which may be stuck to or piled up on the disk in advance of the lifting device or pocket will engage the edge of the arm or wiper, and, as 90 the disk continues to rotate, will be displaced laterally and prevented from approaching the registering point. The movement of the arm which is preferably imparted thereto by a cam, is so timed that the 95 arm will move inward quickly immediately in the rear of the lifting device, will then remain stationary for an interval and then be slowly withdrawn in time to clear the path 100 for the passage of a coin which is properly seated in the pocket. To displace any coin which may adhere to the coin in the pocket, which would not be engaged by the edge of the arm, I prefer to provide the wiper with a part which will move across the coin 105 pocket and while not disturbing the coin which is properly seated in the pocket will engage and displace any coin which may adhere thereto. For this purpose the inner 110 end of the arm is provided with an extension which projects beyond the tapered nose 23^a and has that face adjacent to the disk cut away so that a single coin may pass beneath the same. The arrangement of this 115 projecting end of the arm or wiper is such that upon the inward movement of the wiper the projection will pass across the coin seat and remove the surplus coin or coins. Preferably, this projecting end of 120 the arm or wiper is provided with a spring-pressed plunger 28 which in its normal position is spaced a short distance from the face of the disk and has its nose rounded or beveled so that it will easily ride over a single coin but will displace a surplus coin. 125 The arm or wiper 23 is positively moved through a suitable connection with the operating means for the mechanism. As here shown the arm or wiper 23 has a rearwardly projecting pin 25 which engages a slotted 130

finger 26 carried by a slide plate 27 having horizontal reciprocatory movement which is imparted thereto in a manner which will be hereinafter described and which serves to move the wiper about its axis. Not only do the coins adhere to and pile up on the disk along the path of the coin lifting devices, but when there is a large number of coins in the hopper and particularly if the coins happen to be a trifle sticky, as sometimes results from moisture and dust, they will work up across the disk near its center and occasionally a coin will be forced into the path of the coin lifting devices beyond the wiper. In order to prevent any such coin from reaching the registering position I have provided the disk with an opening 29 arranged in advance of each pocket or coin lifting device and have arranged in the rear of the disk a "kicker" which is in the form of a spring-pressed finger 30 having its nose arranged to ride normally over the rear face of the disk and to be projected forcibly through the opening 29 when the latter is brought in alinement therewith thus dislodging any coin which may extend across the opening. There may, if desired, be more than one of these kickers or spring-pressed fingers and in the present instance I have provided a second one arranged slightly beyond the first and arranged to enter the aperture 29 immediately before the aperture reaches the registering position of the coin. Thus, if by any possibility a coin should be forced into the path of the pocket beyond the first kicker it will be displaced by the second kicker, thus eliminating any possibility of it entering the registering position.

Inasmuch as a coin of any one of the several denominations may be lifted by any one of the lifting devices or pockets I have provided means differentially movable by the coins as they are moved by the disk to actuate the counting mechanism and thus operate the registering mechanism in accordance with the diameter of the coin, and, as no two coins of different values have the same diameter the registration is also in accordance with the value of the coins. This differentially movable mechanism may be of any suitable character but that here shown has been found to operate satisfactorily in practice. It comprises a differentially movable member in the form of a lever 31 pivotally mounted, as shown at 32, at one side of the vertical plane of the axis of the disk and having a downwardly curved portion extending across said plane close to the disk. A spring 33 tends to resist the outward movement of this lever and holds the same normally in a position to be engaged and actuated by the coins. In the present instance the free end of the lever is connected with one end of the spring 33, the other end

of which is connected with a fixed part of the frame. As a coin carried by the movable member or disk approaches its highest position its edge engages the lower edge of the differentially movable member or lever 31 and this member is elevated a distance corresponding to the diameter of the coin. In the present construction of the machine I have provided means for lifting the coin off the inner lug 21 and supporting the same upon a fixed support while it is in engagement with the lever 31. This is accomplished by means of a pointed finger or support 34 carried by a transversely extending plate or shield 35 and arranged to engage the lower edge of each coin so that the latter will be moved upon the support by the continued movement of the lifting device. It will be understood that the coin remains in engagement with the disk and with the rear lug 20 throughout its engagement with the differentially movable lever, its lower edge only being in engagement with the fixed support. After the coin has passed the lever it is discharged through a suitable chute 36, one wall of the upper portion of which is formed by the shield 35, into the drawer or coin receptacle 3, where the conductor may have access to the same to enable him to have on hand an ample supply of change. Inasmuch as the value of each coin has been registered before it has been deposited in the drawer there is no possibility of the conductor or other collector defrauding the company, either accidentally or intentionally, as he must account for the amount of money shown upon the register.

The register or counting mechanism may be of any suitable character. That here shown is of an ordinary type and comprises a series of counter wheels 37 mounted upon a shaft 38 journaled on a suitable supporting frame 39. The units wheel is rigidly secured to the shaft and rotates therewith and the movement of the units wheel is transferred to the successive wheels by means of transfer mechanism 40 of a well known type. The amount of the registration is controlled by the amount of rotation imparted to the shaft 38 and I have provided means whereby the amount of this rotation is directly controlled by the amount of movement imparted to the differentially movable member or lever 31. This result may be secured in various ways but as here shown the shaft 38 has a bevel pinion 41 meshing with a corresponding pinion 42 on a shaft 43 which is journaled in suitable bearings 44 carried by the frame of the machine. Mounted upon the shaft 43 and held against rotation relatively thereto is a pinion 45 which is so connected with the lever 31 as to move with the same. In the form here shown the pinion is rigidly secured to the shaft 43 and the shaft itself has vertical movement with

the lever. To this end the pinion is provided with a grooved collar 46 into which extends a bifurcated finger or plate 47 carried by the lever. The shaft is so connected with the pinion 42 that it may have longitudinal movement relatively to that pinion but will cause the pinion to rotate in unison therewith. This may be accomplished by providing the shaft with a longitudinal slot through which the connecting means for the pinion extends. Means are also provided for retaining the differentially movable member or lever 31 in adjusted positions. In the present instance the free end of the lever is enlarged, as shown at 48, and provided with teeth adapted to be engaged by a spring-actuated pawl 49. The lever 31 forms the selecting device for the differential operating mechanism for the coins and the movement of this lever controls or selects the number of units which will be added to the counting mechanism. The manner in which the desired movement is imparted to the counter may be varied, but a very simple form of mechanism consists of a series of toothed members or racks 50 arranged parallel one with the other and preferably all carried by a single plate 51 which is mounted on a carriage having reciprocatory movement, as hereinafter described. These several racks are so arranged that when the pinion 45 has been moved into one of its operative positions it will be in alinement with some one of the several racks and the reciprocation of the racks, as they move with the carriage, will cause one of said racks to engage the pinion, rotate the shaft and thus operate the counting mechanism. In the present form of the device the racks are superposed one above the other and their arrangement is in accordance with the relative diameters of the several coins, the value of which they represent. For instance the ten-toothed rack is at the bottom of the series because the dime has the smallest diameter of any coin adapted to be handled by the mechanism; the penny comes second; and the nickel is arranged above the penny. Means are provided for releasing the lever and permitting the same to be moved into its normal position as soon as the registration has been accomplished. In the present device the pawl 49 has secured thereto a pin 52 which projects through a slot in the plate on which the pawl is mounted and extends into the path of the plate 51 carrying the toothed members or racks. The position of this pin with relation to the rack is such that the rack will engage the same and move the pawl into its inoperative position just as the last tooth actuates the pinion. The movement of the plate carrying the several toothed members is so limited that it is never moved beyond the pinion in an operative direction, that is, on its outward movement the last tooth of

whichever rack is in operative position remains in engagement with the teeth of the pinion 45 but moves far enough to actuate the pinion. Preferably the last tooth of each of the several racks comprises a single tooth and thus this last tooth not only serves to prevent the overthrow of the pinion and, consequently, of the registering mechanism, but it also forms a guide which remains in engagement with the pinion and prevents displacement thereof during its downward movement. When the pinion has reached its lowermost position it has passed below the lowermost rack and will not be affected by the return movement of the racks.

The rack supporting plate 51 is mounted on a bracket 53 secured to a carriage 54 which, in the present instance, is a plate having its edges mounted in grooved track members 55. Reciprocatory movement is imparted to this carriage from the handle 15 and, in the present arrangement, this is accomplished by mounting a plate or disk 56 on the shaft and connecting the same with the carriage by means of a pitman 57. This form of mechanism is simple in its operation, of a powerful construction and automatically provides a dwell at the end of each reciprocation which permits the pinion 45 to return to its inoperative position. The disk 56 has in its lower surface a cam groove 58 into which extends a pin 59 rigidly secured to the slideable bar 27 which carries the bifurcated plate to actuate the wiper 23. In this manner the movement of the disk, the actuating racks and the wiper is secured from a single source of power and are properly timed.

The operation of the machine has been fully described in connection with the description of the several parts thereof and it will be apparent that the machine itself is very simple both in its construction and in its operation; that it contains but a few parts and that these parts are so arranged and actuated that there is little likelihood of their being broken or disarranged; that there is very little, if any, probability of the coins becoming wedged or binding at any point during their travel through the mechanism and thus interfering with the operation of the machine. It will be noted that because of the fact that each of the coin-lifting devices is adapted to lift a coin of any one of the denominations which the machine is designed to handle and because the differentially movable member which controls the registering mechanism is actuated by these coins while they are in engagement with the lifting device, thus shortening the path of travel of the coin and simplifying the mechanism, the machine is capable of handling coins very rapidly even though the movable member or disk may be actuated at a relatively low rate of speed. Further-

more, the arrangement and construction of the several parts is such that even when the movable member or disk is operated at a very high rate of speed the coins will be 5 positively handled and their value accurately registered.

While I have shown and described one embodiment of my invention it will be understood that the same has been chosen for the 10 purpose of illustration only and that I do not desire to be limited to the details of construction shown and described, for obvious modifications will occur to a person skilled in the art.

Having thus fully described my invention, what I claim as new and desire to secure by Letters Patent, is:—

1. In a coin registering mechanism, a register adapted to register coins of several different denominations, a hopper adapted to hold coins of the several denominations indiscriminately mixed, a movable member arranged within said hopper and provided with a device to lift the coins in said hopper 25 to a discharging point, said device being adapted to lift coins of all denominations registrable, means to dislodge from said movable member all coins except that properly located in said device, and a single differentially movable part located in the path 30 of said device, operatively connected to said register and adapted to be engaged successively by each coin lifted by the said device as it is moved past and moved different distances according to the size of the coin and irrespective of the denomination thereof, and a discharging point for the coins beyond said part.

2. In a coin registering mechanism, a hopper arranged to hold coins of different sizes, a rotatable disk mounted in said hopper having devices thereon to move coins of different sizes from said hopper to a discharging point, means in engagement with said disk to dislodge surplus coins therefrom to insure proper registration, a register, an actuating device therefor comprising a differentially movable part arranged to engage each coin on said disk as it is carried past, and a discharging point through which said coins are discharged after their disengagement from said differentially movable part, said discharging point being located beyond said differentially movable part.

3. In a coin registering mechanism, a hopper arranged to hold coins of different sizes, an inclined rotatable disk mounted in said hopper and having pockets each adapted to receive coins of different denominations and 50 to lift the same from said hopper to a discharging point, a register, an actuating mechanism for said register having a differentially movable part arranged at the edge of said disk in advance of the point at 55 which said coins are to be discharged and

adapted to be engaged by the edges of the coins in said pockets and moved different distances according to the denominations of the coins as the latter are moved past the same by said disk.

4. In a coin registering mechanism, a hopper arranged to hold coins of different sizes, an inclined rotatable disk mounted in said hopper and having pockets each adapted to receive coins of different denominations and to lift the same from said hopper to a discharging point, means in engagement with said disk to dislodge surplus coins therefrom to insure proper registration, a register, an actuating device therefor comprising a differentially movable part arranged at one side of said disk to engage the edges of the coins in said pockets and move different distances according to the denominations of the coins as the latter are 70 moved past the same by said disk.

5. In a coin registering mechanism, a hopper comprising a movable member having a lug arranged near one edge thereof, a second lug arranged at one side and 75 slightly in advance of the first-mentioned lug, said lugs coöperating to form a pocket, said hopper also having a flange arranged along the edge of said movable member and coöperating with said lugs to retain a coin 80 in engagement therewith, a register, a mechanism actuated by said coin while it is in engagement with one of said lugs for controlling the operation of said register, and a fixed member to move said coin out of 85 engagement with the other of said lugs and support the same while it is in operative engagement with said operating mechanism.

6. In a coin lifting device, a hopper adapted to hold coins of several denominations indiscriminately mixed, said hopper comprising an inclined rotatable disk having a device adapted to lift coins of all denominations from said hopper, a flange arranged about the periphery of said disk, 105 said device comprising a pair of lugs projecting upwardly from the surface of said disk, one of said lugs being arranged near the periphery of said disk and the other of said lugs being arranged in advance of 110 the first-mentioned lug and inwardly thereof, said lugs coöperating one with the other and with the flange to support a coin on said disk when the latter is rotated, the inner lug being of a height no greater than 115 the thickness of the thinnest coin to be handled, whereby surplus coins can fall back into the hopper.

7. In a coin registering mechanism, a hopper comprising an inclined rotary disk, 125 and a wall diverging from and coöperating with said disk, said wall having a yielding portion arranged adjacent to the lower edge of said disk.

8. In a coin registering mechanism, a 130

6

hopper comprising a movable member to move coins of different sizes from said hopper to a discharging point, a register, actuating mechanism for said register having an operable part arranged in the path of the coins carried by said movable member and in advance of the point at which said coins are discharged, a selective device, an operative connection between said selective device and the operable part of said actuating mechanism to cause said selective device to be moved into different positions by the coins as they are moved past said operable part of said actuating mechanism, and a plurality of other devices arranged to coöperate, respectively, with the selective device when it is in different positions to cause said register to be actuated in accordance with the value of each coin.

20 9. In a coin registering mechanism, a hopper comprising a movable member to move coins of different sizes from said hopper to a discharging point, a register, actuating mechanism for said register having an operable part arranged in the path of the coins carried by said movable member and in advance of the point at which said coins are discharged, a pinion connected with said register and capable of axial movement into different positions, an operative connection between said pinion and the movable part of said actuating mechanism to cause said pinion to be moved into different positions by coins of different sizes as those coins are moved past said movable part of said actuating mechanism, a plurality of racks of different lengths arranged to coöperate, respectively, with said pinion when it is in different positions to cause said register to be actuated in accordance with the value of each coin.

10 10. In a coin registering mechanism, a hopper comprising a movable member to move coins of different sizes from said hopper to a discharging point, a register, actuating mechanism for said register having an operable part arranged in the path of the coins carried by said movable member and in advance of the point at which said coins are discharged, a pinion connected with said register and capable of axial movement into different positions, an operative connection between said pinion and the movable part of said actuating mechanism to cause said pinion to be moved into different positions by coins of different sizes as those coins are moved past said movable part of said actuating mechanism, a plurality of racks of different lengths arranged to coöperate, respectively, with said pinion when it is in different positions to cause said register to be actuated in accordance with the value of each coin, and means for imparting reciprocatory movement to said racks.

11. In a coin registering mechanism, a hopper comprising an inclined rotatable disk having pockets each capable of lifting coins of different sizes from said hopper and moving the same to a discharging point, a register, a pinion operatively connected with said register and capable of axial movement, a plurality of racks of different lengths, means for imparting movement to said racks, a movable device arranged in the path of the edges of the coins carried by said inclined disk in advance of the point at which said coins are to be discharged, and an operative connection between said pinion and said movable device, whereby said pinion will be moved different distances by coins of different sizes.

12. In a coin registering mechanism, a hopper comprising an inclined rotatable disk having pockets each capable of lifting coins of different sizes from said hopper and moving the same to a discharging point, a register, a pinion operatively connected with said register and capable of axial movement, a plurality of racks of different lengths, means for imparting movement to said racks, a lever pivotally mounted on an axis substantially parallel with the axis of rotation of said disk and having one edge arranged in the path of the coins carried by said inclined disk, a spring tending to hold said lever in a position to be engaged by said coins, and a connection between said lever and said pinion whereby coins of different sizes will move said pinion into operative relation with different ones of said racks.

13. In a coin registering mechanism, a hopper comprising a movable device to move coins of different diameters therefrom, a register, a reciprocatory support, a plurality of racks of different length carried by said support, a pinion operatively connected with said register, and a device actuated by the coins to move said pinion into operative relation with racks of different length according to the diameters of the coins.

14. In a coin registering mechanism, a hopper comprising a movable member to move coins of different diameters therefrom, a register, selective actuating mechanism for said register comprising a movable part arranged to be engaged by the edges of the coins as they are moved by said movable member, and a fixed part arranged to engage the coins simultaneously with their engagement with said movable part of said actuating mechanism and to support said coins while they are being moved by said movable member.

15. In a coin registering mechanism, a hopper comprising a rotatable disk having means to move coins of different denominations therefrom, a register, a plurality of racks of different lengths, a pinion operatively connected with said register and

capable of axial movement, a movable device connected with said pinion and arranged to be engaged by the edges of the coins, as they are moved by said disk, to impart axial movement to said pinion and bring it into alinement with a rack corresponding in length to the denomination of the coin which is in engagement with said movable device, and a fixed member arranged to engage that edge of said coin opposite the edge engaged by said movable device to support the same while it is being moved by said movable member.

16. In a coin registering mechanism, a hopper comprising a movable member to move coins of different diameters therefrom, a register, a plurality of racks of different lengths, a pinion operatively connected with said register and capable of axial movement, and means for holding said pinion in its adjusted position while it is being actuated by said rack, a movable device arranged to be engaged by the edges of said coins on said movable member, a fixed member to engage said coins simultaneously with their engagement with said movable device and to support the same while they are being moved by said movable member.

17. In a coin registering mechanism, a hopper comprising a rotatable disk having devices to move coins of different diameters from said hopper, a register, a plurality of reciprocatory racks of different lengths, a pinion operatively connected with said register and adapted to be moved into operative relation with any one of said racks, a lever connected with said pinion and arranged to be engaged by the coins as they are moved by said disk, and a fixed member arranged near the face of said disk to support the coins while they are in engagement with said lever.

18. In a coin registering mechanism, a hopper comprising a rotatable disk having devices to move coins of different diameters from said hopper, a register, a plurality of racks of different lengths, a pinion operatively connected with said register and adapted to be moved into operative relation with any one of said racks, a lever connected with said pinion and arranged to be engaged by the coins as they are moved by said disk, and means to hold said lever and said pinion in adjusted positions until the rack with which said pinion is in operative relation has completed its operative movement.

19. In a coin registering mechanism, a hopper comprising a rotatable disk having devices to move coins of different diameters from said hopper, a register, a plurality of racks of different lengths, a pinion operatively connected with said register and adapted to be moved into operative relation with any one of said racks, a lever connected with said pinion and arranged to be en-

gaged by the coins as they are moved by said disk, and means to hold said lever and said pinion in adjusted positions until the rack has completed its operative movement, and means actuated by said rack to release said lever.

20. In a coin registering mechanism, a hopper comprising a rotatable disk having devices to move coins of different lengths from said hopper, a register, a plurality of reciprocatory racks of different lengths, a pinion operatively connected with said register and adapted to be moved into operative relation with any one of said racks, a lever connected with said pinion and arranged to be engaged by the coins as they are moved by said disk, and means to hold said lever and said pinion in adjusted positions until the rack with which said pinion is in operative relation has completed its operative movement, and means actuated by said rack at the end of its operative movement to release said lever.

21. In a coin registering mechanism, a hopper comprising a rotatable disk having devices to move coins of different diameters from said hopper, a register, a plurality of movable racks of different lengths, a pinion operatively connected with said register and adapted to be moved into operative relation with any one of said racks, a lever connected with said pinion and arranged to be engaged by the coins as they are moved by said disk, said lever being provided with teeth, a spring-pressed pawl to engage said teeth to hold said lever in adjusted positions and a tripping device connected with said pawl and arranged to be engaged by the rack as it reaches the end of its operative movement.

22. In a coin registering mechanism, a hopper comprising a movable member to move coins of different diameters therefrom, a register, a movable member having secured thereto a series of racks of different lengths, a pinion operatively connected with said register and movable into alinement with any one of said racks, a lever arranged to be engaged by the coins and connected with said pinion.

23. In a coin registering mechanism, a hopper comprising a rotatable disk to move coins of different diameters from the hopper, a register, selective operating mechanism for said register comprising a differentially movable member arranged to be engaged by the coins as they are moved by said disk, and means to hold said movable member in adjusted positions until the operation of said register has been completed.

24. In a coin registering mechanism, a hopper comprising a movable member to move coins of different diameters therefrom, a register, a reciprocatory plate having secured thereto a series of racks of different

- lengths, a pinion operatively connected with said register and movable into alinement with any one of said racks, and a lever arranged to be engaged by the coins and connected with said pinion.
25. In a coin registering mechanism, a hopper comprising a movable member to move coins of different diameters therefrom, a register, a movable plate having secured thereto a series of racks of different lengths, a pinion operatively connected with said register and movable into alinement with any one of said racks, and a lever arranged to be engaged by the coins and connected with said pinion, an operating device, and a connection between said operating device and said plate to impart movement to the plate and to cause a dwell at the end of the movement of said plate in one direction.
- 10 26. In a coin registering mechanism, a hopper comprising a movable member to move coins of different diameters therefrom, a register, a reciprocatory plate having a series of racks of different lengths, means to impart reciprocatory movement to said plate, a pinion operatively connected with said register and movable into alinement with any one of said racks, and a device operatively connected with said pinion and arranged to be engaged by the coins as they are moved by said movable member, whereby said pinion is moved into alinement with the rack corresponding with the denomination of the coin with which said device is in engagement.
- 15 27. In a coin registering mechanism, a hopper comprising a movable member to move coins of different diameters therefrom, a register, a movable plate having secured thereto a series of racks of different lengths, a pinion operatively connected with said register and movable into alinement with any one of said racks, a lever arranged to be engaged by the coins and connected with said pinion, an operating device, and a crank and pitman connection between said operating device and said plate to impart movement to the plate and to cause a dwell at the end of the movement of said plate in one direction.
- 20 28. In a coin registering mechanism, a hopper comprising a movable member to move coins of different diameters therefrom, a register, a reciprocatory plate having secured thereto a series of racks of different lengths, a pinion operatively connected with said register and movable into alinement with any one of said racks, a lever arranged to be engaged by the coins and connected with said pinion, and means to move said plate in its operative direction a distance sufficient to cause any one of the racks thereon to fully operate said pinion but to prevent the last tooth of said rack being moved out of engagement with said pinion, whereby said last tooth prevents the overthrow of said pinion.
- 25 29. In a coin registering mechanism, a hopper comprising a movable member to move coins of different diameters therefrom, a register, a reciprocatory plate having secured thereto a series of racks of different lengths, a pinion operatively connected with said register and movable into alinement with any one of said racks, a lever arranged to be engaged by the coins and connected with said pinion, and means to move said plate in its operative direction a distance sufficient to cause any one of the racks thereon to fully operate said pinion but to prevent the last tooth of said rack being moved out of engagement with said pinion, whereby said last tooth prevents the overthrow of said pinion, the last teeth of the racks on said plate being arranged in alinement and adapted to remain in engagement with said pinion upon the completion of its outward movement, whereby said last teeth form a lock to prevent the movement of said pinion during its return to normal position.
- 30 30. In a coin registering mechanism, a hopper comprising an inclined rotary disk having devices on the front thereof to move coins from said hopper, said coins resting on said disk, openings in said disk in advance of the respective devices and of the coin mounted therein, said openings being of a diameter less than the diameter of the smallest coin moved, and a spring-pressed finger mounted on a fixed support at the rear of said disk and having its end bearing against said disk as the latter rotates and adapted to enter each of said openings, whereby surplus coins not properly mounted in said devices will be thrown from said disk back into the hopper.
- 35 31. In a coin registering mechanism, a hopper comprising a movable member having devices on the front thereof for moving coins to registering position, said movable member having an opening arranged in front of each of said devices, a register, means arranged along the edge of said movable member and controlled by the coins thereon for actuating said register, a wiper movable across the path of said coin-moving devices, and a spring-pressed finger arranged between said coin-controlled means and said wiper and mounted on a fixed support in the rear of said movable member bearing against the same and adapted to enter each of said openings when the latter are brought into alinement therewith by the movement of said movable member.
- 40 32. In a coin registering mechanism, a hopper comprising a rotary disk having devices to move coins from said hopper, a register, and means controlled by said coins for actuating said register, a wiper, and means to cause said wiper to move bodily

over each of said coin moving devices as said devices approach said registering means.

33. In a coin registering mechanism, a 5 hopper comprising a rotary disk having devices to move coins from said hopper, a register, and means controlled by said coins for actuating said register, a wiper, and means to cause said wiper to move over each 10 of said coin moving devices as said devices approach said registering means, and a spring-pressed plunger carried by that part of said wiper which passes over said devices.

34. In a coin registering mechanism, a 15 register, means controlled by the coins for actuating said register, a movable member having devices for moving the coins to registering position, each of said devices being adapted to support a single coin, and a device 20 movable across the path of said coin-moving devices in advance of said register actuating means.

35. In a coin registering mechanism, a 25 register, means controlled by the coins for actuating said register, a movable member having a series of coin moving devices to move coins into registering position, a member movably mounted adjacent to said movable member, and means for moving said 30 member across the path of said coin-moving devices and into close proximity with said movable member in the rear of each coin-moving device and to withdraw said member in advance of the following coin-moving device.

36. In a coin registering mechanism, a 40 register, means controlled by the coins for actuating said register, a movable member having a series of coin moving devices to move coins into registering position, an arm pivotally mounted near the edge of said movable member, and means for actuating said arm to cause it to be quickly moved across the path of said coin lifting devices 45 and in close proximity to said movable member immediately in the rear of each coin moving device and to be slowly withdrawn from said path in advance of the following coin-moving device.

50 37. In a coin registering mechanism, a register, means controlled by the coins for actuating said register, a movable member having a series of coin moving devices to move coins into registering position, an arm 55 pivotally mounted near the edge of said movable member, and means for actuating said arm to cause it to be moved into a position extending across the path of said coin-moving devices and in close proximity 60 to the face of said movable member to cause said arm to remain for an interval in such position and to withdraw said arm in advance of the following coin-moving device.

38. In a coin registering mechanism, a 65 register, means controlled by the coins for

actuating said register, a movable member having a series of coin moving devices to move coins into registering position, an arm pivotally mounted near the edge of said movable member, means for actuating said 70 arm to move it across the path of said coin-moving devices immediately in the rear of each of said devices, and a part carried by said arm and adapted to move across each coin lifting device as said arm moves in the 75 rear thereof.

39. In a coin registering mechanism, a register, means controlled by the coins for actuating said register, a movable member having devices for moving coins to registering position, said movable member having an opening arranged in front of each of said devices, and a plurality of spring-pressed members supported in the rear of said movable member and adapted to successively enter the openings in said movable member as the latter advances the respective coin moving devices toward registering position.

40. In a coin registering mechanism, a 90 register, means controlled by the coins for actuating said register, a rotary disk having a series of pockets for moving the coins into registering position, said disk having an opening in advance of each of said pockets, 95 and a plurality of spring-pressed fingers arranged in the rear of said disk, spaced apart and adapted to successively enter each of said openings as they approach the registering position.

41. In a coin registering mechanism, a 100 coin receptacle having means to move coins therefrom, a register, a coin-controlled device for actuating said register, said device comprising a movable member, a detent to 105 retain said movable member in an adjusted position during the actuation of said register, and means to retain said detent in an inoperative position during the movement of said movable member to its normal position.

42. In a coin registering mechanism, a 110 coin receptacle having means to move coins therefrom, a register, a coin-controlled device for actuating said register, said device 115 comprising a lever movable into different positions, a detent arranged to engage said lever and hold the same in an adjusted position, and means for disengaging said detent at the end of the registering operation 120 and holding the same in its disengaged position until said lever has returned to its normal position.

43. In a coin registering mechanism, a 125 register adapted to register coins of several different denominations, a hopper adapted to hold coins of the several denominations indiscriminately mixed, a movable member arranged within said hopper and provided with a device to lift the coins in said hopper 130

to a discharging point, said device being adapted to lift coins of all denominations registrable, means to dislodge from said movable member all coins except that properly located in said device, and a single differentially movable part located in the path of said device, operatively connected to said register and adapted to be engaged successively by each coin lifted by the said device as it is moved past and moved different distances indirectly proportional to the denomination of said coin so registered, whereby

coins of high denomination and small size are registered with equal facility along with coins of low denomination and large size, 15 and a discharging point for coins beyond said part.

In testimony whereof, I affix my signature in presence of two witnesses.

FRANK B. KENNEDY.
